UNITED STATES PATENT OFFICE.

WILLIAM C. PALMER, OF CHICAGO, ILLINOIS.

INTERNAL-COMBUSTION ENGINE.

1,183,904.

Specification of Letters Patent.

Patented May 23, 1916.

Application filed November 9, 1914. Serial No. 870,969.

To all whom it may concern:

Be it known that I, WILLIAM C. PALMER, a citizen of the United States, residing at Chicago, in the county of Cook and State of Illinois, have invented certain new and useful Improvements in Internal-Combustion Engines, of which the following is a specification.

One of the objects of the present invention 10 is the production of a light-weight, powerful motor or engine of the internal-combustion or explosion type, preferably of the style wherein an explosion occurs in each cylinder for each revolution, whereby a 15 small number of cylinders only are required to obtain the desired smooth running of the device.

A further feature of the invention resides in the production of a construction 20 wherein the charge or mixture of explosive gas is drawn into the cylinder under the action of spring-pressure, preferably, though not necessarily, in connection or association with an auxiliary fresh air supply taken 25 through the crank casings and pistons, whereby to secure an efficient scavenging or cleaning of the cylinders and an effective expulsion of the exploded gases.

Another salient feature of the improved 30 construction incorporating the preferred embodiment of the invention is the employment of multiple or double springs one within the other to secure an extensive expansion, but occupying, however, a relatively 35 small space, these springs being employed to operate the supplemental plunger to draw in the charge or mixture. I also provide for the efficient cooling of the engine and springs, and preferably employ the scavenging air to assist in such cooling action.

In order that those skilled in this art may have a full and complete understanding of the invention, a preferred embodiment of the same has been illustrated in the accompanying drawings forming a part of this specification, and to which reference should be had in connection with the following detailed description of the construction and operation. In the various views, like characters refer to the same parts. From a consideration of the illustration and description, the attainment of the above specified and other objects will be apparent.

In these drawings: Figure 1 is a central, 55 vertical, longitudinal section through a two-cylinder engine; Fig. 2 is a vertical cross-

section through one of the cylinders showing the movable parts in a different position; Fig. 3 is a central, vertical section between the cylinders, and Fig. 4 is a section on line 4—4 of Fig. 3.

Referring to the drawings, it will be apparent that the main casting 10 is provided with a plurality of bearings 11, 12, and 13 for the accommodation of a crank-shaft 14 equipped with a fly-wheel 15. In the style of engine illustrated, this casting has two vertically-arranged adjacent cylinders 16 and 17, each equipped with its own independent crank-case, 18 and 19 respectively, the cylinders being in direct communication with their respective crank-casings, as is clearly illustrated.

In this two-cylinder engine, the sliding power-piston 20 of the cylinder 16 is associated with its portion of the crank-shaft by the usual connecting-rod 21 and the reciprocating piston 22 of the cylinder 17 is similarly connected to the crank-shaft by a connecting-rod 23. Each of these hollow pistons has an upstanding, centrally-disposed, apertured boss, 24 and 25 respectively, each provided with a port through the piston and equipped with downwardly-closing, spring-actuated valves 26 and 27 respectively.

As is illustrated, the cylinders are supplied with the outstanding radiation ribs 28, 29, and between the lower portions of the cylinders there is provided a downwardly-extended, right-angle passage 29, (Figs. 3 and 4), opening at its upper end into the space between the cylinders. The closure 30 for the enlarged or lower end of the air passage 29 is held in place against the casing by a wing-nut 31 on the threaded end of a rod 32, the inner end of which takes into the internal boss 33. Fulcrumed on this rod is a lever 34 carrying upwardly-closing valves 35 and 36, the former establishing and breaking communication between the passage 29 and the crank-casing 18, and the latter controlling communication between the passage 29 and the companion crank-casing 19, the valves being so arranged on the lever arm that when one is closed the other is open, and vice versa.

The ribs 28 on the upper portions of the cylinders are circular in form while the ribs 37 on the lower portions of the cylinder are continuous, extending around not only the outer surfaces of the cylinders 16 and 17 but also around the walls forming the cen-

tral passage 29, all as is clearly illustrated in Figs. 3 and 4.

Fastened to opposite sides of the cylinders by screws 60 engaging bosses 61 are a pair of sheet-metal plates 62 and 63, spaced away from the cylinders and having their forward portions 64 made divergent and the rear portions 65 convergent so as to receive between them an adequate supply of cooling air and direct it toward the rear side of the back cylinder to more efficiently obtain its cooling action. These plates, as will be apparent, form a sort of casing or open shell around the cylinders.

Each cylinder has an intake-port 38 controlled by a spring-pressed valve 39, and is also supplied with a plurality of discharge ports 40, 40, associated with ribbed exhaust manifolds 41 and 42.

Each cylinder in its upper portion has reciprocable therein a hollow plunger 43 provided through its top-wall with a port 44 communicating with a plurality of radiating ports 45, 45 and controlled by an upwardly-closing spring-pressed valve 46. Each cylinder at its top has an upwardly-projecting, externally ribbed, axial extension 47 providing an internal cylindrical compartment or chamber 48 accommodating an outer expansion spiral-spring 49 and an inner telescoping expansion-spiral-spring 50 associated together so as to operate in series or conjunction with one another by means of a thin, metal, interposed sleeve 51, the lower end of which has a flange 52 underlying the lower end of the outer spring 49 and the inner or upper end of which has a shoulder 53 overlying the corresponding end of the internal spring 50, the inner end of the sleeve having also a reduced extension 54 adapted to slide on and be guided by a central stud 55 accommodated inside of the inner spring. As is clearly shown, the lower end of the inner spring 50 bears against a central boss on the top wall of the sliding plunger 43. In this way the downward pressure of both springs is exerted on the plunger, tending to depress the same. The parts are so constructed that when the plunger is at its uppermost position, as illustrated in the right-hand cylinder of Fig. 1, the compartment or chamber 48 is substantially filled with the telescoped and interfitting springs, sleeve, stud, and valve-operating parts, so that the compartment can contain or hold only a gaseous content of small volume under these circumstances.

Each cylinder is, of course, equipped with its own spark plug or other ignition device 56 and 57 respectively. In order that the charge inside of the hollow plunger may be fired or exploded, the exterior surface of each plunger is equipped with an annular groove 58 which communicates with one or more holes or apertures 59 extending

through the cylindrical wall of the plunger, the groove 58, of course, being in register with the spark plug of the cylinder when conditions are proper for the explosion of the mixture, as shown in the right-hand portion of Fig. 1.

Operation: The operation of this appliance takes place substantially as follows: Assuming in any one cylinder that the plunger and the piston which partially telescopes therewith are at the upper range of their movements with a compressed charge or mixture between them ready for firing the explosion, as illustrated in the right-hand cylinder of Fig. 1, the igniting device is operated and fires the charge by means of the groove 58 and the openings 59. This explosion pushes the piston downwardly, exerting rotative effort on the crank-shaft in the usual manner. The plunger, however, remains in its uppermost position, because the pressure between it and the piston is greater than the downward pressure of the coöperating springs 49 and 50. As soon, however, as the pressure between the plunger and piston is reduced sufficiently so that the pressure of the springs on the plunger overcomes it, which will ordinarily occur as soon as the piston uncovers the exhaust ports 40, then the plunger will be pressed down by its springs and will draw in the fresh discharge above it through the intake-port 38, the valve 39 opening for this purpose, as will be readily understood, and the valve 46 of the plunger remaining closed. This downward movement of the plunger not only draws in a new charge above it, but it also assists in the rapid expulsion of the exploded gases through the discharge-ports which are made of ample capacity.

During the downward stroke of the piston the corresponding crank-case valve 35 or 36, as the case may be, was held closed, owing to the compression of the air in the crank-case due to such movement of the piston. During the down stroke of the piston, the valve 26 was maintained closed by reason of the gas pressure above it and its own coöperating spring. As soon, however, as the piston uncovered the exhaust or discharge ports and thereby reduced the pressure above the piston, the pressure of the compressed air below the piston and in the crank-case was sufficient to open the piston valve 26 and 27, as the case may be, and centrally discharge the fresh air into the cylinder between the piston and the plunger. This discharge will occur at approximately the same time that the plunger is descending toward the piston under the influence of its springs, which results in the rapid discharge of the exploded gases, the air assisting in expelling the gases and cleaning the cylinder. In this way a direct coöperation is obtained between the action

of the descending plunger and the centrally-discharged air through the piston.

The exploded gases having been thus discharged and the charge of mixture having been taken or drawn in above the plunger, when the piston ascends it will approach the plunger, partly entering the same, and in so doing, will compress the intervening air which will act as a cushion between the parts. Such upward movement of the piston and plunger causes a closure of the valve 39 and an opening of the valve 46, so that the gas charge above the plunger is now transferred to within the plunger and when the plunger and piston reach their uppermost position the mixture will be then ready for firing or ignition, as previously explained. This upward travel of the piston will cause an opening of the crank-case valve and the drawing in to the crank-case of a supply of air from between the cylinders through the passage 29 ready for compression in the crank-case during the subsequent descent of the piston, as explained above. Where a plurality of cylinders are employed in close juxtaposition, as is usual in engines of this type, the hottest zone and that which requires the most cooling, is between the two cylinders, and by thus drawing in the air at this point a positive and direct circulation of air is effected between the cylinders assisting in maintaining them cool. Stated differently, the cooling air around the exterior of the cylinders is drawn in through the crank-casings and used to assist in the expulsion of the exploded gases in the cylinders and in their cleansing.

The cycle of operation in the two cylinders is alike, but it should be noted that no springs are required for the crank-case valves 35 and 36 mounted on the lever 34, because one of these valves will always be open while the other is closed and vice versa. That is, when air is being drawn into one crank-case it is being compressed in the other so that there is no conflict in the action of the valves.

It should be observed further that an engine of this type is somewhat self-regulating because the extent of movement of the plungers and, consequently, the charge which they will suck in, will depend somewhat upon the speed at which the engine is operating, the higher the speed the less charge drawn in and the lower the speed the greater the charge, whereby the engine will have a tendency to maintain a uniform speed.

From a consideration of this preferred embodiment of the invention and its functions it will be appreciated that the objects of the invention are accomplished therein. That is to say, the engine may be constructed so as to be of light weight and still be smooth in its running operation due to

the fact that there is an explosion in each cylinder during each revolution, the charge or mixture being drawn in under spring action, the cylinders effectively cooled both interiorly and exteriorly and cleaned internally by the air admitted centrally through the piston, such central distribution being most efficient for the rapid and complete expulsion of the useless gases.

Various minor mechanical changes may be incorporated in a structure of this character without departing from the essence of the invention and without sacrificing any of its substantial benefits and advantages, and it is, therefore, to be understood that the invention is not limited and restricted to the precise and exact structural features shown and described.

I claim:

1. In an internal-combustion engine, the combination of a cylinder provided with an intake-port, a power-piston slidable in said cylinder, a valved plunger slidable in said cylinder and located between the cylinder intake-port and said piston, and a plurality of telescoping springs arranged in series and adapted to operate said plunger, substantially as described.

2. In an internal-combustion engine, the combination of a cylinder provided with an intake-port, a power-piston slidable in said cylinder, a valved plunger slidable in said cylinder and located between the cylinder intake-port and said piston, a plurality of telescoping springs arranged in series and adapted to act on said plunger, and means connecting the opposite ends of said springs to secure their cumulative effect substantially as described.

3. In an internal combustion-engine, the combination of a plurality of cylinders, a piston slidable in each, a closed crank-case for each of said cylinders, means to conduct air from between said cylinders to said crank cases, a valve for each of said crank-cases, a crank-shaft, a connecting-rod between the crank-shaft and each of said pistons, and a valve for each of said pistons controlling the passage of the crank-case air through the piston into the cylinder, substantially as described.

4. In an internal-combustion engine, the combination of a cylinder provided with intake and exhaust ports, a valved power-piston slidable in said cylinder, a power shaft, a connection between said piston and power shaft, means to cause said valve to open to admit air through the piston into the cylinder to assist in the expulsion of the exploded gases, a valved plunger slidable in said cylinder and located between the cylinder intake-port and said piston, and means unconnected with said shaft adapted to operate said plunger, substantially as described.

5. In an internal-combustion engine, the

- combination of a cylinder provided with intake and exhaust-ports, a valved power-piston slideable in said cylinder, means to cause said valve to open to admit air through the piston into the cylinder to assist in the expulsion of the exploded gases, a valved plunger slideable in said cylinder and located between the intake-port and said power-piston, and spring-means to operate said plunger, substantially as described.
6. In an internal-combustion engine, the combination of a cylinder provided with intake and exhaust-ports and a compartment forming an extension of the cylinder-cavity, a valved power-piston slideable in said cylinder, means to cause said valve to open to admit air through the piston into the cylinder to assist in the expulsion of the exploded gases, a valved plunger slideable in said cylinder and located between the intake-port and said power-piston, and spring-means housed in said compartment and adapted to operate said plunger, substantially as described.
7. In an internal-combustion engine, the combination of a cylinder provided with intake and exhaust-ports, a valved power-piston slideable therein, a closed crank-case, a crank-shaft, a connecting-rod between said crank-shaft and piston, the valve of the piston being adapted to permit the passage of air therethrough from the crank-case to assist in the expulsion of the exploded gases and in the cleaning of the cylinder, a valved plunger slideable in said cylinder and located between the cylinder intake-port and said power-piston, and means unconnected with said crank-shaft adapted to operate said plunger, substantially as described.
8. In an internal-combustion engine, the combination of a cylinder provided with intake and exhaust-ports and a compartment forming an extension of the cylinder cavity, a valved power-piston slideable in said cylinder, a closed crank-case, a crank-shaft in said case, a rod connecting said crank-shaft and piston, the valve of the piston being adapted to permit the passage of air therethrough from the crank-case to assist in the expulsion of the exploded gases and in the cleaning of the cylinder, a valved plunger slideable in said cylinder and located between the cylinder intake-port and said power-piston, and spring-means housed in said compartment and adapted to operate said plunger, substantially as described.
9. In an internal-combustion engine, the combination of a cylinder provided with intake and exhaust-ports, a power-piston slideable in said cylinder, a power-shaft, a connection between said piston and shaft, a closed crank-case, a crank-shaft in said case, a rod connecting said crank-shaft and pis-
- ton, a valve controlling the admission of air to the crank-case, a valve controlling the passage of the crank-case air through the piston into the cylinder, a valved-plunger slideable in said cylinder and located between the intake-port and said power-piston, and means unconnected with said power-shaft adapted to operate said plunger, substantially as described.
10. In an internal-combustion engine, the combination of a cylinder provided with intake and exhaust-ports, a power-piston slideable therein and having a substantially central aperture therethrough, a closed crank-case, a crank-shaft in said case, a connecting-rod between said crank-shaft and piston, a valve controlling the admission of air to the crank-case, a valve controlling the passage of the crank-case air through the aperture through said piston into the cylinder, a valved plunger slideable in said cylinder and located between the intake-port and said power-piston, and spring-means to operate said plunger, substantially as described.
11. In an internal-combustion engine, the combination of a plurality of cylinders each provided with intake and exhaust ports, a power-piston slideable in each of said cylinders, a closed crank-case for each of said cylinders, means to conduct air from between said cylinders to said crank cases, a valve for each of said crank-cases, a crank-shaft for each of said crank-cases, a connecting rod between each of said power-pistons and said crank-shafts, a valve in each of said pistons controlling the passage of the crank-case air through the piston into the cylinder, a valved plunger slideable in each of said cylinders and located between the cylinder intake-port and the corresponding power-piston, and means to operate said plungers, substantially as described.
12. In an internal-combustion engine, the combination of a plurality of cylinders each having admission and exhaust-ports, a casting inclosing said cylinders and open at the front and rear to permit the passage of air past the cylinders, a power-piston slideable in each of said cylinders, a closed crank-case for each of said cylinders, means to conduct air from between said cylinders to said crank cases, a valve for each of said crank-cases, a crank-shaft in said crank-cases, a connecting-rod between the crank-shaft and each of said power-pistons, and a valve for each of said pistons controlling the passage of the crank-case air through the piston into the cylinder, substantially as described.
